UNITED STATES PATENT OFFICE.

EDWIN A. GUINZBURG, OF NEW YORK, N. Y.

DESIGN FOR A BATHING-CAP.

44,840.

Specification for Design.

Patented Nov. 4, 1913.

Application filed June 5, 1913. Serial No. 772,006. Term of patent 7 years.

To all whom it may concern:

Be it known that I, EDWIN A. GUINZBURG, a citizen of the United States, residing in the city, county, and State of New York, and whose post-office address is 85 Fifth avenue, in said city, have invented a new, original, and ornamental Design for Bathing-Caps, of which the following is a specification, reference being had to the accompanying drawing, forming part hereof, in which—front elevation; and Fig. 3 is a rear elevation of the bathing cap.

I claim:

The ornamental design for a bathing cap as shown.

EDWIN A. GUINZBURG.
